United States Patent Office

Des. 221,830
Patented Sept. 14, 1971

221,830

CARCASS SPLITTER

Ralph Karubian, 2001 W. Gage Ave.,
Los Angeles, Calif. 90047

Filed Aug. 17, 1970, Ser. No. 24,525

Term of patent 14 years

Int. Cl. D8—02; D7—99

U.S. Cl. D8—64

FIG. 1 is a perspective view, from one side, of a carcass splitter showing my new design.

FIG. 2 is a perspective view, from the opposite side thereof.

I claim:

The ornamental design for a carcass splitter, substantially as shown.
